DESIGN FOR A TIRE

Burgess Darrow, San Marino, Calif., assignor to
Wingfoot Corporation, Wilmington, Del., a cor-
poration of Delaware

Application December 3, 1937, Serial No. 73,339

Term of patent 14 years

To all whom it may concern:

Be it known that I, Burgess Darrow, a citizen
of the United States, residing at 586 Winston
Ave., San Marino, in the county of Los Angeles
and State of California, have invented a new,
original, and ornamental Design for a Tire, of
which the following is a specification, reference
being had to the accompanying drawing, forming
part thereof.

Fig. 1 is a plan view of a portion of the tire
embodiment my new design;

Fig. 2 is a fragmentary side elevation of the
same; and

Fig. 3 is a sectional view taken on the line
3—3 of Fig. 1.

I claim:

The ornamental design for a tire, as shown.
BURGESS DARROW.
